HIGH VACUUM CHAMBER

Hugh R. Smith, Jr., Oakland, Calif., assignor to Stauffer Chemical Company, New York, N.Y., a corporation of Delaware

Filed Nov. 9, 1959, Ser. No. 851,878

7 Claims. (Cl. 230—101)

The present invention relates in general to an improved pumping geometry for vacuum chambers, and more particularly to a chamber structure having maximized pumping area defining the chamber for attaining high pumping speeds to maintain a high vacuum therein.

In various processes and apparatus it is necessary to evacuate liberated gas from reaction chambers and to establish and maintain a vacuum therein. This is normally accomplished by the utilization of conventional vacuum pumps, such as diffusion pumps, or the like, which may also be combined with backing pumps to attain the desired degree of vacuum. In certain circumstances, this conventional solution is found to be unsatisfactory because of physical space limitations. Without limitation, an example of the foregoing is found in electron-beam furnaces utilized in the purification and casting of metals. In at least certain electron-beam processes for casting and purifying metals, there are employed high-vacuum techniques for the purpose of removing gases liberated from metals melted by electron-beam bombardment. In order for such processing to proceed with maximum efficiency, it is highly important for relatively large quantities of liberated gas to be very rapidly removed from the processing region, i.e., from the direct volume of melted metal. While it is theoretically possible to provide desired pumping speeds by the addition of a suitable number of conventional vacuum pumps about the reaction or furnace chamber, a practical difficulty is encountered in the physical space limitations present. It is well known that conventional vacuum pumps have substantial physical sizes, which will be noted to be related to the pumping speed of such pumps. In order to attain a very high pumping speed operable in a limited volume, it is necessary to provide a large plurality of large vacuum pumps in direct communication with such volume or region. It has been found that certain physical difficulties are involved in this multiplication of pumping means, for the physical size of the pumps places an upper limit on the number of pumps which can be placed closely adjacent to any limited volume.

The physical disposition of vacuum pumps at any substantial distance from a limited volume to be maintained at a particular vacuum has been found to be ineffectual to prevent serious pressure excursions in the volume of interest. These effects are particularly deleterious when the pressure is such that the mean free path of the vapor or gas molecules is of the order of the minimum dimension of the enclosure, or greater. Under these conditions the geometrical impedance to the flow of the gases and vapors into the pumps will be at a maximum. Thus the pumps must be very closely coupled through the widest possible orifices to the vacuum enclosure to be effective. The net pumping speed is related to the area over which pumping is accomplished. It thus follows that no matter how efficient vacuum pumps may be, there may yet remain a serious difficulty in removing large volumes of gas from relatively limited regions to maintain a substantially constant vacuum in such region. This particular problem, while present in various processes, directly arises in the above-noted example of electron-beam casting of metals in vacuum wherein very substantial quantities of gas are almost instantaneously liberated at certain points in the process, depending upon the purity

2

of the particular material being processed. While it has been found possible in commercial installations employing electron-beam casting to maintain a vacuum of less than one micron of mercury with large oil diffusion pumps and to sustain a pumping speed of more than 30,000 liters per second, further improvements in the vacuum and pumping speed for such applications are beneficial, if not requisite, to additional advances in the field of vacuum metallurgy.

10 The present invention provides a chamber geometry highly suited to the establishment of very large pumping speeds whereby a chamber volume of relatively limited size may be maintained at a very low pressure despite sporadic bursts of gas from materials processed therein.

15 A chamber structure highly suited for a furnace chamber to be used in electron-beam processing of metals in vacuum is herein provided with a maximized defining area which is available for the pumping of gas. In distinction to conventional vacuum chambers wherein a plurality of ports are commonly provided in the walls thereof of communicating with vacuum pumps, the present invention provides a chamber which is itself defined by pump inlets. In accordance herewith it is possible to attain a pumping area that is as large as 80 percent of the total wall area of a chamber to be evacuated. With this chamber structure it is thus possible to attain pumping speeds of the order of hundreds of thousands of liters per second. With such pumping speeds it has been found possible to maintain chambers of limited volume at operating pressures of the order of 0.01 to 0.10 micron while very substantial quantities of gas are liberated within the chamber. In the field of vacuum metallurgy wherein electron-beam melting is employed, for example, it is possible in accordance with the present invention to materially increase the melting rate of metal being purified while at the same time substantially eliminating the evolution of gas bursts in the chamber. The tremendous pumping speed available with the present invention serves to remove gas evolved during the process of casting and purification so rapidly that almost no pressure variations occur within the processing volume, and consequently a materially improved processing is possible. By the utilization of the present invention it is also possible to reduce the overall height of furnace chambers of the type herein discussed, for the physical size of suspended diffusion pumps which normally dictate the minimum chamber dimensions are no longer ruling. As particularly applied to electron-beam vacuum metallurgy, the present invention provides a substantial advancement by the utilization of a maximum amount of the area surrounding the region in which material is being melted to provide pumping for the evacuation of such region.

40 It is an object of the present invention to provide an improved geometry for maximized evacuation of such chamber.

45 It is another object of the present invention to provide an improved structure for a furnace chamber wherein a maximum available wall area is employed to evacuate the chamber.

50 It is yet another object of the present invention to provide an improved furnace chamber structure for an electron-beam furnace.

55 It is another object of the present invention to provide an improvement in the vacuum casting of metals by electron-beam bombardment through the enhanced evacuation of the reaction region therein.

60 Various other possible objects and advantages of the present invention will become apparent to those skilled in the art from the following description of a single preferred embodiment of this invention. No limitation is intended by the terms of the following disclosure, and instead reference is made to the appended claims for a

precise delineation of the true scope of the present invention.

The invention is illustrated as to a single preferred embodiment thereof in the accompanying drawings wherein:

FIG. 1 is a plan view of a furnace chamber with the top thereof removed.

FIG. 2 is a sectional view of a furnace chamber taken in the plane 2-2 of FIG. 1.

The present invention in brief provides a vacuum chamber structure including a pumping wall in large part defining the chamber. This pumping wall preferably extends about the chamber and is formed of a plurality of pumps having a high ratio of inlet openings to physical structure at the inlet end so that the wall is mainly composed of pumping area. A maximized pumping area for the chamber is herein attained by the utilization of pumps having optimized inlet openings. Of particular interest in this respect are strip pumps of quite simple and straightforward construction and which include but a minimum of structural elements tending to restrict the pump inlet. These pumps are found to be readily combined into a multiple pumping unit that is admirably suited to define a chamber or the like that is intended to be evacuated. By the provision of a maximized pumping area defining a chamber to be evacuated, the present invention provides a maximum pumping speed for such chamber to thereby most efficiently and rapidly remove gases which may be evolved in such chamber. In particular, the geometry of the present invention is admirably suited to the rapid removal of large quantities of gas from a very limited volume. It is possible in accordance herewith to locate an extremely large pumping area immediately adjacent and surrounding a region wherein gases may be evolved so that substantially no delay results between the evolution of gas and the removal of same from the region of interest. In this manner, it is possible to attain a very substantial vacuum within a region wherein gases are being evolved and also to maintain this substantial vacuum without pressure variations of substantial magnitude therein. Even though relatively large quantities of gas may be evolved at periodic or sporadic intervals, the very substantial pumping speed which is realized by the present invention and the immediate proximity of the pumping area to the region of interest herein provides for the immediate removal of such gases to thereby maintain within the region a very substantial vacuum.

Considering now a single preferred embodiment of the present invention as illustrated in the drawings, and referring to these drawings, there will be seen to be provided a furnace chamber 11, illustrated in plan view in FIG. 1 and containing, for example, a mold 12 into which melted metal is adapted to flow during electron-beam casting of same. This chamber 11 is desired to be maintained at a high vacuum, as of the order of 0.01 micron pressure. With the introduction of metal, as indicated by the billet 13, into the chamber and the melting of this billet therein, a substantial quantity of gas may be evolved within the chamber. This gas must thus be very rapidly removed in order to maintain a substantial vacuum in the furnace chamber. In the interest of clarity various portions of the electron-beam furnace are not illustrated in the drawings of this application but only the mold 12 and billet 13 of metal to be melted are illustrated. The chamber 11 may be defined at the bottom thereof by a solid wall 14 and at the top thereof by a similar wall 16 with the upstanding portion of the chamber between this top and bottom being almost entirely defined by pumping area.

There is herein provided about the periphery of the chamber 11 and defining same a plurality of strip jet pumps 17 to 28 which form a pumping wall of the chamber. The term "strip pump" will be seen to identify the physical structure of the pumping means, inasmuch as same include elongated strips. Thus, the structure of the pump 17, for example, includes a pair of vertical strips

31 and 32 extending upward from and in communication with a boiler, or the like, 33. Each of the upstanding strips 31 and 32 consists of a hollow member adapted to conduct a pumping medium such as a vapor from the boiler 33, and each is provided with slots along the trailing edges of the strip through which such pumping medium is forced. These strip slots are oriented so that the pumping medium, such as a vapor, will escape from the strips under pressure generally rearwardly of the strip, as indicated by the arrows 34 in FIG. 1. The high velocity vapor flow, as is established by the escape of pumping medium from the strips 31 and 32, will be seen to operate to entrap or entrain gas molecules in the vicinity of the strips to thereby move same to the rear of the pump whereat same may be exhausted. In the present instance there may be provided in connection with the rear of each of the strip pumps a conventional backing pump 36, so that the strip pump 17, for example, exhausts into the intake of the pump 36 which operates to discharge the pumping medium and entrained gas molecules into the atmosphere about the chamber. The strips 31 and 32 are preferably formed of a very small cross-section so as to occupy a minimum of volume while yet establishing a relatively large flow of vapor or the like to accomplish maximum pumping. Suitable connections to the boiler 33 serve to produce the vapor, or the like, employed as the pumping medium in these pumps, as, for example, by the heating of a liquid therein.

The chamber 11 of the present invention is defined by the plurality of pumps 17-28 with common radial walls 37-48 being provided about the circumference of the chamber 11 between the strips of the separate pumps. These walls 37-48 are vertically disposed in general parallelism with the strips of the individual pumps and serve to separate the adjacent pumps. The walls are also preferably disposed radially of the chamber 11 about same with an exterior wall 49 being disposed about the outer circumference of these radial walls in attachment with the chamber top 16 and bottom 14 to thereby complete the chamber structure.

It will be seen that upon energization of the strip pumps 17-28 by operation of the boilers thereof to establish a desired flow of pumping medium through the individual strips of the separate pumps, there will be produced a pumping action tending to evacuate the chamber 11. The pumping medium, such as a vapor, which is forced from the boilers of the pumps through the strips thereof to pass outwardly and rearwardly from these strips between the radial walls separating the adjacent pumps will serve to produce a pumping action of very substantial magnitude. It will be noted from the structure illustrated in FIG. 1 in particular that a very small physical volume is occupied by the front strip 31 of the pump 17, for example, and by the edge of the radial walls which define the periphery of the chamber 11. The wall about the chamber 11 is thus substantially defined by pumping area between the front strip of each of the strip pumps and the edges of the radial walls disposed between the separate pumps. The physical structure of the rear strip of each of the pumps is not particularly critical in the present instance inasmuch as same does not limit the inlet area to the pumps. It is possible in accordance with the present invention to provide a chamber structure wherein the upstanding walls thereof are composed almost entirely of pumping area rather than physical structure. In accordance herewith there have been constructed vacuum chambers wherein the peripheral wall is composed of 80 percent pumping area. Such a vacuum chamber has further been employed as a furnace chamber for electron-beam bombardment metal purification wherein a high vacuum is requisite to proper completion of the purification reaction. A material improvement in casting and purification reactions of this type have been realized with the vacuum chamber of the present invention inasmuch as it has been possible to maintain a pressure of the order of 0.01 to 0.1 micron of

pressure in a furnace wherein commercially feasible melting rates are attained. Such a furnace chamber provides a pumping speed of the order of hundreds of thousands of liters per second, so that greatly increased melting rates are possible while yet preventing gas bursts by the extremely rapid removal of gases evolved during the processing.

The foregoing description of a preferred embodiment of the present invention is herein set forth as an example of particular structure wherein the basic concepts of the invention are achieved. Alternative structures are possible in accordance with the invention and thus, for example, an ordinary diffusion pump may have the top thereof reoriented so that the pump orifices are integral with the pump jets, to thereby improve the pumping geometry in accordance with the invention. In this manner it is possible to approach theoretical efficiencies for conventional pumps and to thereby provide for extremely high pumping rates, so that there may be maintained a very substantial vacuum even though relatively large quantities of gases are evolved in the evacuated region. The present invention will thus be seen from the foregoing to provide a chamber for evacuation which is in substantial part defined by pumping area rather than by structural members. It will be appreciated that gas molecules liberated within a chamber at low pressure will rapidly move thereabout and will, in the normal course of events, encounter and rebound from structural elements defining the chamber so as to thereby materially contribute to the pressure within the chamber. Particularly at low pressures is the foregoing of importance, so that a relatively small quantity of gas evolved within a chamber maintained at a low pressure serves to materially increase the pressure of the chamber.

The present invention operates to prevent pressure excursions from the evolution of gas within the chamber by eliminating the great majority of structural members against which gas molecules may impinge. Viewed in another manner, the present invention provides a maximum pump inlet area in closely spaced relation to the particular region or volume desired to be evacuated and maintained at high vacuum. Consequently, the present invention overcomes certain serious limitations of the prior art and provides for a substantial advancement in the field of vacuum pumping, particularly as same is related to such processes and apparatuses as suffer from the evolution of gas within evacuated regions.

What is claimed is:

1. An improved vacuum chamber comprising a plurality of vacuum pumps disposed about a closed path and having inlet apertures the outline structures of which being in contiguous array defining a wall of said chamber, and additional walls engaging the outline structures of said pump inlets at the ends thereof for completing enclosure of said chamber which is thus surrounded by said pumps and adapted to be maintained at a vacuum even during evolution of gas within the chamber.

2. An improved vacuum chamber comprising a plurality of strip jet pumps disposed in side-by-side relation about a closed path to define a chamber wall, said pumps each having a maximized inlet area with respect to physical structure at one end so that the structural outlines thereof define said chamber wall substantially consisting of the aggregate of the structural outlines of the pump inlet areas, and means including a top and a bottom sealingly engaging said pumps at the ends thereof to close said chamber, said pump inlets extending from the top to the bottom.

3. An improved furnace chamber comprising top and bottom walls connected by a circumferential vacuum communicating wall, a plurality of strip jet pumps each including at least one thin elongated strip having rear-

wardly directed slots longitudinally thereof and means forcing a pumping fluid medium into said strips and out of said slots to establish a pumping action, said pumps being disposed contiguously between said top and said bottom walls to form said vacuum communicating wall, and thin walled radial partitions forming the side walls of said pumps and disposed between said strips of adjacent pumps to define respective pump inlets, whereby said chamber is defined about the circumference thereof by the structural outline of said pump inlets to maximize the vacuum communicating area of the chamber.

4. An improved vacuum chamber structure for maintaining a high vacuum during the evolution of gas therein and comprising a plurality of thin radial walls disposed about the circumference of a closed path defining the peripheral boundary of said chamber, at least one source of pumping fluid medium, a plurality of thin elongated strips disposed parallel to said radial walls with at least one strip between each of the adjacent walls, said strips having slots longitudinally thereof along trailing edges thereof with said slots directed outwardly of said chamber and being connected to said source of pumping fluid medium whereby the latter is forcibly ejected from said strips generally outwardly of said chamber, and means including top and bottom walls engaging said radial walls at opposite ends thereof for closing said chamber above and below said closed path, the open spaces defined by the inner ends of said radial walls and said top and bottom walls forming the outlet for gas to be evacuated from said chamber.

5. An improved structure for a circular vacuum chamber comprising a plurality of vertically elongated jet vacuum pumps each including a boiler with at least one vertical strip communicating therewith, said strip having a thin, hollow cross-section with a curved leading edge and slots along both sides of the trailing edge whereby pumping fluid medium from said boiler escapes rearwardly from said strips, top and bottom walls defining said chamber, means mounting said pumps about the periphery of said walls with the leading edge of said strips facing the chamber, and only thin, radial walls forming walls of said pumps and extending between said top and bottom walls and separating said strips circumferentially of the chamber, whereby the upright peripheral wall of the chamber is defined by said pumps with a maximized pump-in area about the chamber.

6. An improved vacuum chamber comprising top and bottom walls, and a peripheral vacuum communicating wall connecting said top and bottom walls and including a plurality of contiguous vacuum pumps having inlet openings of maximized dimension relative to structural area thereof extending between said top and bottom walls, with said inlet openings being directed inwardly with respect to the vacuum communicating wall to thereby provide for maximum pumping speed from the said chamber so defined.

7. Apparatus according to claim 1 in which the vacuum pumps are disposed about a circle and have elongated inlet apertures.
